UNITED STATES PATENT OFFICE.

WALTER T. JOHNSTON, OF MACON, GEORGIA.

DESIGN FOR A HANDLED WRENCH-HEAD.

SPECIFICATION forming part of Design No. 24,518, dated July 30, 1895.

Application filed April 12, 1895. Serial No. 545,532. Term of patent 14 years.

To all whom it may concern:

Be it known that I, WALTER T. JOHNSTON, a citizen of the United States, residing at Macon, in the county of Bibb and State of Georgia, have invented and produced a new and original Design for a Wrench Head and Handle, of which the following is a specification.

Reference is to be had to the accompanying drawings, forming a part of this specification, in which—

Figure 1 is a perspective view of a wrench head and handle embodying my new design, and Fig. 2 is a top view of the head.

The leading feature of my design consists in the novel configuration of the head and handle, as shown, the head having a rounding

and transversely-serrated top surface and projecting at opposite ends beyond the handle, one projecting end rounding vertically on convex lines and merging into the top surface and presenting a bifurcation, and the opposite projecting end being concaved at the under side, said concaved surface and the adjacent end of the rounding top surface being joined by a slight convexity, as at *a*.

I claim—

The design for a wrench head and handle herein shown and described.

WALTER T. JOHNSTON.
